[57] **CLAIM**

The ornamental design for a combined ceiling fan motor housing, switch housing, and blade irons unit, as shown and described.

DESCRIPTION

FIG. 1 is a perspective view of a combined ceiling fan motor housing, switch housing, and blade irons unit, showing our new design;

FIG. 2 is an additional perspective view showing environmental structure, the broken lines forming no part of the design;

FIG. 3 is a front elevational view thereof;

FIG. 4 is a right side elevational view thereof;

FIG. 5 is a rear elevational view thereof;

FIG. 6 is a left side elevational view thereof;

FIG. 7 is a bottom view thereof; and,

FIG. 8 is a top view thereof.
